Specification forming part of Design No. 6,083, dated August 20, 1872.

Specification describing a Design for a Shawl-Pattern, invented by FREDERICK WINK, of Philadelphia, Pennsylvania.

Design for a Shawl-Pattern.

The figure in the accompanying drawing clearly represents my design, the main features of which are the stripes A, B, and C, all of which are of the same general character, and composed of parallel minor ribs or stripes of different widths, and colors or shades of color. The stripe A has a central rib, a, ornamented by transverse and angular lines and dots and diamonds, as clearly represented in the drawing. The stripe B is composed mainly of two similar ribs, d, of greater width than, but having the same characteristics as, the rib a.

Irrespective of the colors employed, I claim—

The design for a shawl-pattern, substantially as described and as represented in and by the accompanying drawing.

In testimony whereof I have signed my name to this specification in the presence of two subscribing witnesses.
